Inventor,

David H. Pingree;

By *A. Bluhm*,
Attorney.

UNITED STATES PATENT OFFICE.

DAVID H. PINGREE, OF MELROSE, MASSACHUSETTS.

LOCK.

1,259,128.

Specification of Letters Patent. Patented Mar. 12, 1918.

Application filed June 23, 1917. Serial No. 176,576.

To all whom it may concern:

Be it known that I, DAVID H. PINGREE, a citizen of the United States, and a resident of Melrose, in the county of Middlesex and 5 Commonwealth of Massachusetts, have invented certain new and useful Improvements in Locks, of which the following is a full, clear, and exact specification.

The purpose of this invention is the construction of a key-actuated lock wherein the key, after the bolt has been thrown from the inside of the apartment, cannot be pushed in from the outside and a skeleton key used for opening the door. Another result of my 15 invention is the effecting of means whereby the locking of the door automatically closes the key-hole against prying eyes.

In carrying my invention into effect I provide the bolt of the lock with a plate which 20 screens the key hole when the bolt is thrown, thereby shutting off vision through the hole and preventing the key from being pushed in from the outside of the door.

Referring to the drawings forming part 25 of this specification, Figure 1 is an elevation of a lock embodying my improvement, a part of the case being broken away to expose the interior. Fig. 2 is an elevation of the lower part of the same. Fig. 3 is a sectional view on the line X—X in Fig. 1. Fig. 4 is a perspective view of the bolt alone, having my device formed thereon.

The lock upon which my improvement is shown as applied is of a well known construction, comprising a case composed of two separable sections 1 and 2, keyholes 3 and 4 and a bolt 5. From the bolt descends a finger 6 preferably integral therewith, and disposed to be close beside the line joining the two keyholes, when the bolt is in its unlocked position. Rigid with the lower end of this finger is an elbow 7 passing beneath the level of the keyholes and terminating in an angular plate 9, the latter being arranged to be outside the range of the keyholes when the bolt is in its unlocked position, but to be brought therein when the bolt is thrown to its locked position, as indicated by Fig. 2.

Consequently, when the door is unlocked, the plate or guard 9 is out of the way of the keyhole, and the key can be inserted and removed without interference; so also

after the key has been inserted from the outside of the apartment, the key can be 55 freely removed after locking the door; but after the key has been introduced from within and the bolt thrown, the guard 9 comes between the ward of the key and the inner keyhole 3, and the key can no longer be 60 withdrawn.

It is, of course, not desirable to provide a guard as 9 for the outer keyhole 4, inasmuch as then the key could not be removed when locking the door from the outside; 65 and it is no drawback to have the key incapable of removable after locking the door from the inside, for practically all people leave the key in the lock at such times.

I prefer to form the guard 9 with a wing 70 10 positioned to remain close beside the range of the keyholes after the bolt has received its locking throw, as an aid in unlocking the door from the outside. After the key has been inserted, it cannot be turned 75 in the wrong direction, as is possible with similar locks not given my improvement, but the manipulator immediately notes he can turn the key in but one direction, and that the correct one. 80

As shown in Fig. 2, the presence of the guard 9 in the range of the keyholes after locking the door, entirely closes the same to any inquisitive eye.

A further advantage derived from the 85 wing 10 is the hindrance thereby given to picking the lock by means of a bent wire. If it were not for this wing, the key could be turned from the outside to carry its ward toward the right, as viewed in Fig. 2, and 90 thereby leave a clear space from the keyhole to the bolt and its ward; but by providing the wing 10, the key cannot be turned backward, and if it is turned oppositely it remains a barrier between the keyhole and the bolt effectually stopping the passage of 95 a wire to the bolt.

What I claim is:

1. A lock comprising a case having a keyhole, and a bolt formed with a downwardly 100 extended finger, a horizontal elbow projecting from the lower end of said finger below said keyhole, and a guard-plate rising from the said elbow, the plate and finger being spaced to stand at opposite sides of the keyhole when the bolt is in its unlocked posi- 105

tion, and the plate to come in the range of the keyhole when the bolt is in its locking position.

2. A lock comprising a case having a key-hole, and a bolt formed with a downwardly extended finger, a horizontal elbow projecting therefrom below the level of the key-

hole, and a winged plate rising from the extremity of said elbow.

In testimony that I claim the foregoing 10 invention, I have hereunto set my hand this 20th day of June, 1917.

DAVID H. PINGREE.
